The ornamental design for an insole, as shown and described.

DESCRIPTION

FIG. 1 is a top, front, left side perspective view of an insole for a right foot showing our new design;

FIG. 2 is a bottom, rear, left side perspective view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front side elevational view thereof;

FIG. 8 is a rear side elevational view thereof;

FIG. 9 is a cross sectional view taken along line 9-9 of FIG. 4; and,

FIG. 10 is a cross sectional view taken along line 10-10 of FIG. 4.

The design for a left foot insole is the mirror image of the right foot insole shown in FIGS. 1-10.

The surface area between the broken lines on the heel pad of the insole forms no part of the claimed design.

The broken lines are for environmental purposes and form no part of the claimed design.
